US00D957365S

(12) **United States Design Patent** (10) **Patent No.:** **US D957,365 S**
(45) **Date of Patent:** **** Jul. 12, 2022**

(54) **HEADPHONE**

(71) Applicant: **Harman International Industries, Incorporated**, Northridge, CA (US)

(72) Inventor: **Pohsun Lee**, Shenzhen (CN)

(73) Assignee: **Harman International Industries, Incorporated**, Northridge, CA (US)

(**) Term: **15 Years**

(21) Appl. No.: **29/719,410**

(22) Filed: **Jan. 3, 2020**

(51) LOC (13) Cl. **14-01**

(52) U.S. Cl.

USPC **D14/223**

(57) **CLAIM**

The ornamental design for a headphone, as shown and described.

DESCRIPTION

FIG. 1 is a front perspective view of a headphone showing the new design in a first embodiment;

FIG. 2 is a rear perspective view thereof;

FIG. 3 is a front elevational view thereof;

FIG. 4 is a rear elevational view thereof;

FIG. 5 is a side elevational view thereof;

FIG. 6 is an opposite side elevational view thereof;

FIG. 7 is a top view thereof;

FIG. 8 is a bottom view thereof;

FIG. 9 is a front perspective view of the headphone in a second embodiment, showing a mirror image of the headphone of FIGS. 1-8;

FIG. 10 is a rear perspective view thereof;

FIG. 11 is a front elevational view thereof;

FIG. 12 is a rear elevational view thereof;

FIG. 13 is a side elevational view thereof;

FIG. 14 is an opposite side elevational view thereof;

FIG. 15 is a top view thereof; and,

FIG. 16 is a bottom view thereof.

The broken lines in the figures depict portions of the headphone that form no part of the claimed design.
